UNITED STATES PATENT OFFICE.

WILLIAM E. SWEET, OF DOWAGIAC, MICHIGAN.

INTERNAL-COMBUSTION ENGINE.

1,272,570.

Specification of Letters Patent. Patented July 16, 1918.

Application filed August 6, 1917. Serial No. 184,683.

To all whom it may concern:

Be it known that I, WILLIAM E. SWEET, a citizen of the United States, residing at Dowagiac, county of Cass, State of Michigan, have invented certain new and useful Improvements in Internal-Combustion Engines, of which the following is a specification.

This invention relates to improvements in internal combustion engines.

The objects of this invention are:

First, to provide an internal combustion engine which is economical in the consumption of fuel.

Second, to provide an internal combustion engine in which both the fuel and the air for forming the combustible mixture are heated before passing through the carbureter.

Third, to provide improved means for heating the air and the intake manifold.

Fourth, to provide an internal combustion engine with a pair of carbureters, one of which is designed for the use of the lighter hydrocarbons, such as gasolene, and the other of which is intended to be used with heavier hydrocarbons, such as kerosene.

Fifth, to provide improved means for adjusting and controlling said carbureters.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a partial longitudinal section through the front end of an automobile showing the engine with my improvements in side elevation, portions of the engine being broken away.

Fig. II is a detail horizontal section on a line corresponding to line 2—2 of Fig. I.

Fig. III is a rear elevation of my improved combined exhaust and intake manifolds, and air heating device.

Fig. IV is a partial sectional detail showing features of the construction of the intake conduit.

Fig. V is an enlarged detail section on a line corresponding to line 5—5 of Figs. I and III. 55

Fig. VI is an enlarged detail section on a line corresponding to line 6—6 of Figs. I and III.

Fig. VII is an enlarged detail section on a line corresponding to line 7—7 of Fig. VI. 60

Fig. VIII is an enlarged detail section on a line corresponding to line 8—8 of Figs. I and IX, showing details of the construction of the fuel heater.

Fig. IX is a sectional detail on a line corresponding to the curved line 9—9 of Fig. VIII. 65

Fig. X is a plan view of the gasolene carbureter throttle controlling means, showing the spring detent in full lines and in dotted lines. 70

Fig. XI is a sectional detail view through the dash, and foot board, on a line corresponding to line 11—11 of Fig. X, showing details of construction of the gasolene carbureter throttle controlling means. 75

In the drawing similar reference characters refer to similar parts throughout the several views and the sectional views are taken looking in the direction of the little arrows at the ends of the section lines. 80

Referring to the drawings, the reference characters 1, 2 and 3 indicate the dash, hood, and radiator, respectively, of an automobile, and the reference character 4 indicates the foot board thereof. The reference character 5 indicates an internal combustion engine, portions of which have been broken away for convenience in illustration. 85

The parts above referred to are conventionally illustrated as forming parts of a Ford automobile. It is to be understood, however, that my invention is capable of being applied to other types of engines. The reference character 6 indicates the exhaust pipe and the reference characters 7 and 8 indicate the kerosene and gasolene carbureters, respectively. Throughout the specification and claims the terms kerosene and gasolene will be used to designate generally the heavier and lighter hydrocarbons, respectively. 90 95

The kerosene carbureter 7 is connected by means of the pipe 9 with the fuel heater 10,

which, as shown in Figs. VIII and IX, consists of an arcuate shaped receptacle clamped to the exhaust pipe 6 and provided with baffle plates 11, which are alternately disposed to provide a zig-zag passage through the heater. The fuel delivery pipe 9 enters the upper end thereof and the fuel supply pipe 12 connects the heater with a supply of fuel, not shown. By this means, heated fuel is supplied to the kerosene carbureter 7. Gasoline is supplied to the carbureter 8 by means of the pipe 13 which is connected with a suitable supply, not shown.

To insure efficient heating of the combustible mixture and the oil supply for the carbureter, I form the exhaust manifold, intake manifold, and air heating conduits 14, 15, and 16, respectively, in an integral casing, the exhaust manifold being provided with the ports 17 which register with the exhaust ports 18 of the engine cylinder, and the ports 19 which register with the intake ports 20 of the engine cylinders, each of the intake ports 19 in the embodiment illustrated supplying combustible charges to two of the engine cylinders.

The air heating conduit 16 is provided with an air inlet port 21—see Fig. I, which is closer to the gasoline carbureter 8 than to the kerosene carbureter 7, whereby the air delivered to the kerosene carbureter will be heated to a higher temperature than that delivered to the gasoline carbureter. Hot air conduits 22 lead from the opposite ends of the air heating conduit 16 to the air intakes 23 of the kerosene and gasoline carbureters.

The air intakes 23 are provided with "chokers" which are operated through the cranks 24, the free ends of which are pivotally connected to the actuating rod 25, the forward ends of which extend beyond the radiator 3 so that it is accessible to the operator while cranking the engine. I also provide means for operating the choker from the dash comprising the rod 26 which is connected to the rod 25 at one end, the opposite end thereof projecting through the dash and being provided with a handle 27 whereby it may be operated.

The throttle for the kerosene carbureter 7 is controlled through the link 28 and operating mechanism on the steering column, not shown, in the same manner in which the gasoline carbureter throttle is controlled in the ordinary Ford construction.

I also provide a throttle for the gasoline carbureter 8 which is operated through the link 29, the rear end of which is pivotally connected to the crank 30 of a bell crank lever, the horizontal arm 31 of which constitutes a foot pedal for controlling the gasoline carbureter throttle. The foot pedal 31

is urged upwardly by the spring 32 so as to hold the gasoline carbureter throttle normally in a closed position. In order to hold the throttle open while the engine is being cranked, I provide a spring retracted detent 32' which the spring 33 urges to the position shown in dotted outline in Fig. X, 70 in which position it is inactive.

When it is desired to crank the engine, the foot pedal 31 is depressed and the detent 32' is moved outwardly over the foot pedal and the foot pedal is then released. The spring 33 thereupon urges the foot pedal upwardly against the detent 32' and produces sufficient frictional contact between the foot pedal and the detent to hold the latter in the position shown in full lines in Fig. X and 80 the detent prevents the foot pedal 31 from moving upwardly far enough to completely close the gasoline throttle. After the engine is cranked, the operator merely depresses the foot pedal whereupon the detent 85 is retracted by the spring 33 and upon releasing the foot pedal the gasoline throttle is closed.

At any time during the operation of the engine when the combustible mixture formed by the kerosene carbureter is too lean to produce the power required, the foot pedal may be depressed, whereupon the gasoline carbureter will supply a richer combustible mixture to the engine.

The reference characters 35 indicate the stems of the fuel regulating valves for the two carbureters, the upper ends of which are provided with disks 43 that are connected by means of the bowed link 36. The two 100 valves are actuated by the rod 37, the upper end of which is rotatably mounted in and projects through the dash and is provided with a handle 38 for actuating the same.

An important feature of my invention resides in the disposition of the branches 39 and 40 of the intake conduit 41 which connect with the kerosene and gasoline carbureters respectively. These branches are symmetrically related to the intake conduit 105 110 41 so that the combustible mixture is evenly distributed to the intake ports of the engine.

It is believed that the operation of my improved internal combustion engine will be 115 clear, from the above description, to those skilled in the art.

While I have described and illustrated my invention in its preferred embodiment in connection with portions of a Ford automobile engine, it is to be understood that my invention is not limited to the specific details illustrated and described, but may be used with engines of other types and is capable 120 125 of other adaptations and modifications within the scope of the appended claims.

Having thus described my invention, what I claim as new and desire to secure by Letters Patent, is:

1. In an internal combustion engine, the combination of an intake manifold, an air heating conduit and an exhaust manifold formed integrally therewith and having walls in common therewith so that the intake manifold and air heating conduit are heated thereby, said intake manifold having an intake conduit with oppositely disposed branches symmetrically related thereto, a pair of carbureters one adapted for lighter hydrocarbons, such as gasolene, and the other for the heavier hydrocarbons, such as kerosene, connected to the said branches of said intake conduit, the fuel supply to the carbureters for the heavier fuel being provided with heating means associated with the exhaust to be heated thereby, the air heating conduit being provided with delivery connections from its ends to said carbureters, the air inlet of said air heating conduit being closer to the carbureter for the lighter fuel, fuel feed regulating valves for said carbureters provided with a common actuating means, chokers for said carbureters provided with a common actuating means, and throttles for said carbureters provided with independent actuating means, the gasolene carbureter throttle control means being provided with a spring retracted detent for holding said throttle open.
2. In an internal combustion engine, the combination of an intake manifold, an air heating conduit and an exhaust manifold formed integrally therewith and having walls in common therewith so that the intake manifold and air heating conduit are heated thereby, said intake manifold having an intake conduit with oppositely disposed branches symmetrically related thereto, a pair of carbureters one adapted for lighter hydrocarbons, such as gasolene, and the other for the heavier hydrocarbons, such as kerosene, connected to the said branches of said intake conduit, the fuel supply to the carbureters for the heavier fuel being provided with heating means associated with the exhaust to be heated thereby, the air heating conduit being provided with delivery connections from its ends to said carbureters, the air inlet of said air heating conduit being closer to the carbureter for the lighter fuel, and throttle means for said carbureters.
3. In an internal combustion engine, the combination of an intake manifold, an air heating conduit and an exhaust manifold formed integrally therewith and having walls in common therewith so that the intake manifold and air heating conduit are heated thereby, said intake manifold having an intake conduit with oppositely disposed branches symmetrically related thereto, a pair of carbureters one adapted for lighter hydrocarbons, such as gasolene, and the other for the heavier hydrocarbons, such as kerosene, connected to the said branches of said intake conduit, the fuel supply to the carbureters for the heavier fuel being provided with heating means associated with the exhaust to be heated thereby, the air heating conduit being provided with delivery connections from its ends to said carbureters, the air inlet of said air heating conduit being closer to the carbureter for the lighter fuel, and throttles for said carbureters provided with independent actuating means, the gasolene carbureter throttle control means being provided with a spring refracted detent for holding said throttle open.
4. In an internal combustion engine, the combination of an intake manifold, an air heating conduit and an exhaust manifold formed integrally therewith and having walls in common therewith so that the intake manifold and air heating conduit are heated thereby, said intake manifold having an intake conduit with oppositely disposed branches symmetrically related thereto, a pair of carbureters one adapted for lighter hydrocarbons, such as gasolene, and the other for the heavier hydrocarbons, such as kerosene, connected to the said branches of said intake conduit, the fuel supply to the carbureters for the heavier fuel being provided with heating means associated with the exhaust to be heated thereby, the air heating conduit being provided with delivery connections from its ends to said carbureters, the air inlet of said air heating conduit being closer to the carbureter for the lighter fuel, and throttle means for said carbureters.
5. In an internal combustion engine, the combination of an intake manifold, an air heating conduit and an exhaust manifold associated therewith so that the intake manifold and air heating conduit are heated thereby, a pair of carbureters connected to the said intake conduit, the air heating conduit being provided with delivery connections from its ends to said carbureters, fuel feed regulating valves for said carbureters provided with a common actuating means, chokers for said carbureters provided with a common actuating means, and throttles for said carbureters provided with independent actuating means.
6. In an internal combustion engine, the combination of an intake manifold, an air

heating conduit and an exhaust manifold associated therewith so that the intake manifold and air heating conduit are heated thereby, a pair of carbureters connected to the said intake conduit, the air heating conduit being provided with delivery connections from its ends to said carbureters, and throttles for said carbureters provided with independent actuating means.

10 7. In an internal combustion engine, the combination of an intake manifold, an air heating conduit and an exhaust manifold associated therewith so that the intake manifold and air heating conduit are heated thereby, a pair of carbureters connected to the said intake conduit, the air heating conduit being provided with delivery connections from its ends to said carbureters, and throttles for said carbureters provided with independent actuating means, the gasoline carburetor throttle control means being provided with a spring retarded detent for holding said throttle open.

8. In an internal combustion engine, the combination of an intake manifold, an air heating conduit and an exhaust manifold associated therewith so that the intake manifold and air heating conduit are heated thereby, said intake manifold having an intake conduit with oppositely disposed branches symmetrically related therewith, a pair of carbureters connected to the said branches of said intake conduit, the air heating conduit being provided with delivery connections to said carbureters, the air inlet of said air heating conduit being closer to one carburetor than the other, fuel feed regulating valves for said carbureters provided with a common actuating means, chokers for said carbureters provided with a common actuating means, and throttles for said carbureters provided with independent actuating means.

9. In an internal combustion engine, the combination of an intake manifold, an air heating conduit and an exhaust manifold associated therewith so that the intake manifold and air heating conduit are heated thereby, said intake manifold having an intake conduit with oppositely disposed branches symmetrically related therewith, a pair of carbureters connected to the said branches of said intake conduit, the air heating conduit being provided with delivery connections to said carbureters, the air inlet of said air heating conduit being closer to one carburetor than the other, and throttle means for said carburetor.

10. In an internal combustion engine, the combination of an intake manifold, an air heating conduit and an exhaust manifold associated therewith so that the intake manifold and air heating conduit are heated

therby, said intake manifold having an intake conduit with oppositely disposed branches symmetrically related therewith, a pair of carbureters connected to the said branches of said intake conduit, the air heating conduit being provided with delivery connections to said carbureters, and throttle means for said carbureters.

11. In an internal combustion engine, the combination of an intake manifold, an air heating conduit and an exhaust manifold associated therewith so that the intake manifold and air heating conduit are heated thereby, a pair of carbureters connected to the said intake conduit, the air heating conduit being provided with delivery connections to said carbureters, the air inlet of said air heating conduit being closer to one carburetor than the other, and throttle means for said carbureters.

12. In an internal combustion engine, the combination of an intake manifold, an air heating conduit, and an exhaust manifold disposed between and formed integrally therewith, said intake manifold being provided with an intake conduit having branches symmetrically related thereto, a gasoline carburetor and a kerosene carburetor connected to said branches, the air intakes to said carburetors being connected with the end of said air heating conduit, said air heating conduit being provided with an air inlet nearer to the gasoline connection than to the kerosene carburetor connection, and means for heating the fuel supply of said kerosene carburetor.

13. In an internal combustion engine, the combination of an intake manifold, an air heating conduit, and an exhaust manifold disposed between and formed integrally therewith, a gasoline carburetor and a kerosene carburetor connected to said branches, the air intakes to said carburetors being connected with the end of said air heating conduit, said air heating conduit being provided with an air inlet nearer to the gasoline connection than to the kerosene carburetor connection, and means for heating the fuel supply of said kerosene carburetor.

14. In an internal combustion engine, the combination of an intake manifold, an air heating conduit, and an exhaust manifold disposed between and formed integrally therewith, said intake manifold being provided with an intake conduit having branches symmetrically related thereto, a gasoline carburetor and a kerosene carburetor connected to said branches, the air intakes to said carburetors being connected with said air heating conduit, and means for heating the fuel supply of said kerosene carburetor.

15. The combination with an intake mani-

- fold having intake branches symmetrically related thereto, a kerosene carbureter connected to one of said branches, and a gasolene carbureter connected to the other, and
5 common means for supplying heated air to both of said carbureters arranged so that the supply of air to said kerosene carbureter is normally heated to a higher degree than the air supplied to said gasolene carbureter.
10 16. The combination with an intake manifold, a kerosene carbureter, and a gasolene carbureter connected thereto, and a common means for supplying heated air to both of said carbureters arranged so that the supply of air to said kerosene carbureter is normally heated to a higher degree than the air supplied to said gasolene carbureter.

In witness whereof, I have hereunto set my hand and seal in the presence of two witnesses.

WILLIAM E. SWEET. [L.S.]
